UNITED STATES PATENT OFFICE.

PHILIP O. ROBERTSON, OF ALLENTOWN, PENNSYLVANIA.

SHUTTLE-GUARD.

1,384,807.

Specification of Letters Patent. Patented July 19, 1921.

Application filed March 26, 1921. Serial No. 455,740.

To all whom it may concern:

Be it known that I, PHILIP O. ROBERTSON, a citizen of the United States, residing at Allentown, in the county of Lehigh and 5 State of Pennsylvania, have invented certain new and useful Improvements in Shuttle-Guards, of which the following is a specification.

This invention relates to a shuttle guard 10 for looms and the primary object of the invention resides in the construction of a simple yet effective means whereby a shuttle in flight will be prevented from being deflected and thrown out from the loom during its 15 passage across a lay thereby preventing damage to the loom and other operative parts as well as to the material being woven.

In actual practice it has been found to be 20 a very frequent occurrence during the operation of looms in the manufacture of silk, cloth or fabrics that the shuttles do not properly enter the shuttle box at times resulting in damage to the said shuttle and also the shuttle box as well as causing considerable delay in the operation of the loom.

The primary object of the invention is 25 therefore directed to a novel and improved protector or guide for the shuttle whereby the same will be directed in its proper path of movement to the shuttle box, consequently preventing the shuttle from wearing due to friction with the openings of the shuttle box and in addition preventing splintering or 30 damage thereto with the incident damage to the material being manufactured and further resulting in the loss of time and expense due to improper operation.

A still further object of the invention resides in the provision of a shuttle guard 40 which may be freely raised by the shuttle and not act as a rigid but rather as a loose guard as distinguished from similar rigid guards designed for the same purpose thus preventing any possibility of the shuttle before 45 coming jammed or fastened in changing the shuttle from one position to another with respect to the shuttle box and further allowing the weaver or loom operator to make such change as so desired with facility and ease.

Another and very important object of the 50 invention resides in the provision of a shuttle guard which is extremely simple in construction, consisting of comparatively few parts therefor inexpensive to manufacture, highly efficient in operation and practical in 55 use, capable of being installed on various types of looms, freely adjustable and easily mounted or removed with facility and ease and otherwise constituting an important auxiliary for silk weaving machines and the 60 like rendering the same more efficient.

With these objects in view and others which will be suggested and manifest as the purpose and nature of my invention are revealed in the following specification and 65 drawings, wherein I have shown a preferred embodiment thereof,

Figure 1 is a front elevation of the lay and reed, broken off centrally and showing my shuttle guard mounted adjacent the ends 70 of the shuttle boxes.

Fig. 2 is a vertical, sectional view showing the invention as applied to the sword arm and taken on the line 2—2 of Fig. 1.

Fig. 3 is a vertical, sectional view through 75 the shuttle guard as removed from the sword arm.

Fig. 4 is a front view thereof.

Referring now to the drawings, wherein like parts designate corresponding parts throughout the specification, numeral 5 designates a lay and 6 the sword arm to which it is secured as at 7, 8 the swing reed hanger stand and 9 the shuttle boxes, all of which are of a well known construction and common to 85 this type of loom.

The swing reed hanger stand 8 above referred to, which is attached to the top of the reduced end 9 of the sword arm by a casting 10 carries the novel and improved shuttle 90 guard suspended above the lay and positioned at the entrance of the respective shuttle boxes 9 to guide the shuttles shown and designated by numeral 11 as clearly set forth by Fig. 1 of the drawings. The casting 10 is 95 substantially L-shaped and is provided with an elliptical slot 10^a whereby it may be readily attached to the sword arm and also

permitting the guard to be attached to various widths of swing reed hangers in the manner now to be described.

The top portion 12 of the casting is confined between the flanges 13, 14 of an L-shaped supporting member 15, the top of which is provided with an elliptical slot 16 for receiving the fastening element or locking bolt and nut 17 whereby the casting and 10 supporting elements are securely held in position. The supporting element 15 is also provided with an aperture in its top and near its outer end for receiving a freely and vertically movable bolt 18 which passes 15 through an aperture in the inwardly extending flange 19 of the supporting element as clearly indicated by Fig. 3 of the drawing. The head 20 of the bolt 18 normally lies on the top of the supporting element 15, 20 said bolt supporting an arcuate block 21 to which it is threaded as at 22 which block is provided with a cover 23 preferably of leather or similar material fastened by screws 24 to said block in the manner indicated by Fig. 4 of the drawing.

By reason of its free vertical movement and carried by the supporting element 15, it will be readily seen that the guard as positioned and mounted on the sword arm at 30 the entrance of the shuttle boxes 9 will prevent the shuttles 11 from moving out of their path in their flight since the said guard retains the shuttle in its horizontal position during its flight. The tendency of the 35 shuttles during their flight, is of course to fly upwardly and when the same engages the arcuate covered block 21, it will be prevented from moving out of its proper position and be guided thus preventing damage to the 40 operative parts should the said shuttles be deflected from the machine. Since the adjustment of the guard and casting permit both vertical and lateral movement of the guard, it will be readily recognized that the 45 same may be attached to various widths of swing reed hangers by the bolt and nut shown to meet the required needs and conditions of the particular type of machine where the shuttle guard is to be used.

50 In the accompanying drawings I have illustrated my invention embodied in one form by way of example, and which in practice has been found to be highly satisfactory in obtaining the desired results. It will be 55 obvious however that other embodiments may be adopted and that various changes in the details of construction may be resorted to by those skilled in the art without departing from the spirit and scope of the invention. It is furthermore understood that the 60 invention is not necessarily limited or restricted to the precise elements shown except in so far as such limitations are specified in the subject matter being claimed.

Having shown and described my invention, what I now claim as new and desire to secure by Letters Patent of the United States is:—

1. A shuttle guard comprising a casting adapted to be secured to the sword arm of a loom, a supporting element carried by said casting and laterally adjustable with respect to the reed frame of said loom for suspension over the entrance of a shuttle box and a freely movable guide carried by said supporting element for preventing a shuttle from being deflected out of its true horizontal flight.

2. A shuttle guard comprising a casting adjustably secured to the sword arm of a loom, a supporting element laterally adjustable with respect to the reed frame of said loom and secured to said casting for suspension over the entrance of a shuttle box, and a freely movable guide supported near the outer end of said element for preventing a shuttle from being deflected out of its true horizontal flight.

3. A shuttle guard comprising a casting adapted to be vertically adjusted on the upper end of the sword arm of a loom, a supporting element laterally adjustable with respect to the reed frame of said loom and secured to said casting for suspension over the entrance of a shuttle box, and a freely movable guide having an arcuate block at its lower end and supporting by said element for preventing a shuttle from being deflected out of its true horizontal flight.

4. A shuttle guard comprising a casting 100 adapted to be vertically adjusted on the upper end of the sword arm of a loom, an L-shaped supporting element having side flanges laterally adjustable with respect to said casting for suspension over the entrance 105 of a shuttle box, and a freely vertically movable guide having an arcuate, covered block carried by said supporting element for preventing a shuttle from being deflected out of its true horizontal flight.

5. A shuttle guard comprising a casting adapted to be vertically adjusted on the upper end of a sword arm of a loom, an L-shaped supporting element having side flanges laterally adjustable with respect to 115 said casting for suspension over the entrance of a shuttle box, a freely movable bolt supported near the outer end of the supporting member and a detachable arcuate guide connected to said bolt for preventing a shuttle 120 from being deflected out of its true horizontal flight.

6. A shuttle guard comprising a casting adapted to be vertically adjusted on the upper end of a sword arm of a loom, an L-shaped, substantially wide supporting element having side flanges and a slot in the top thereof for adjustable connection with

said casting whereby the said element may be suspended over the entrance of a shuttle box, a freely movable bolt supported near the outer end of the supporting member and a covered, arcuate guide detachably connected to said bolt for preventing a shuttle from being deflected out of its true horizontal flight.

7. A shuttle guard comprising a casting and a supporting element laterally adjust-

able with respect to the reed frame of a loom and adapted to be secured to a sword arm of said loom, and a guide carried by said supporting element for preventing a shuttle from being deflected out of its true horizontal flight. 15

In testimony whereof, I affix my signature hereto.

PHILIP O. ROBERTSON.
